attorney

UNITED STATES PATENT OFFICE.

CLARENCE E. WAKEFIELD, OF WORCESTER, MASSACHUSETTS, ASSIGNOR TO WAKEFIELD ALL-STEEL WRENCH COMPANY, INC., OF WORCESTER, MASSACHUSETTS, A CORPORATION OF MASSACHUSETTS.

SOCKET WRENCH SET.

Application filed April 1, 1927. Serial No. 180,256.

The present invention relates to socket wrench sets, comprising a plurality of socketed members of graduated sizes, and a common handle or shank, which is provided for use, selectively, with any one of said socketed members.

The invention resides in a compact assemblage of all these parts in a specially constructed holder or container, the latter being of simple and inexpensive construction, and adapted to prevent accidental displacement of the parts of the set, while permitting them to be removed, when desired, with the utmost ease from said container.

Other and further objects of the invention will be apparent from the following detailed description, taken in connection with the accompanying drawings, in which—

Fig. 1 is a top plan view of the improved container with the parts of the wrench set assembled therein.

Fig. 2 is a view in side elevation of the assembly.

Fig. 3 is a transverse sectional view on the line 3—3 of Fig. 1.

Fig. 4 is a perspective view, showing the device employed to retain the wrench set parts in the holder or container.

Like reference characters refer to like parts in the different figures.

A socket wrench set of the type referred to provides as is well known a plurality of similarly shaped socket members, here shown as six in number, and indicated, respectively, by the numerals 1, 2, 3, 4, 5 and 6; said members, as shown, are graduated in size and each has a nut or bolt-receiving socket, here shown as hexagonal in form and adapted to fit a given size of nut or bolt, ranging from a large nut or bolt, for which the member 1 is provided, to a small nut or bolt for which the member 6 is provided, intermediate sizes being taken care of by the socket members 2 to 5 inclusive. In the usual manner, each socketed member provides a polygonal opening 7, all of the openings 7 being of the same size and shape, so as to be capable of operative engagement with the similarly shaped handle or shank member 8, common to all of said socket members.

As here shown, the openings 7 are hexagonal, and the handle member 8 is of hexagonal section, to fit all of said openings 7.

Preferably, as shown in Fig. 1, one end of the shank or handle 8 is bent at right angles, as indicated at 9; either end of the handle can be inserted in any of the socket members, depending upon whether the long portion or the short portion of the handle is to be used as a lever arm.

According to the invention, a shallow tray or holder 10 is provided, said tray 10 being preferably made from a single elongated piece of sheet metal, whose longitudinal edges are bent up to provide parallel side walls 11 and 12, and whose ends are bent up to provide end walls 13 and 14. As shown clearly in Fig. 3, parallel longitudinal cuts 15, 15 are made in the bottom of tray 10, and the material between said cuts is pressed outwardly, from the plane of said bottom to provide an underlying strip 16 which, for its entire length, is spaced below said bottom, being integrally connected at its ends 17, 17 to said bottom; the purpose of this strip will be hereinafter described.

The tray 10 is of a length and width sufficient to receive the bent handle member 8, laid flatwise therein as shown in Fig. 1, and the remaining area of the bottom of said tray accommodates the socket members 1 to 6 inclusive, when laid in a row with their sides against said bottom, and their ends against the side wall 12. In so disposing the socket members 1 to 6 inclusive, the largest member 1 is placed adjacent the end wall 14 of the tray, with the sizes of the other socket members gradually decreasing toward the other end of the tray, so that the smallest member 6 is adjacent the short portion 9 of the handle 8.

As a means of securely holding the wrench set parts thus assembled in the tray 10, a device made of wire, and bent substantially into the form shown in Fig. 4, is employed. As shown in Figs. 3 and 4, this device embodies at one end a rectangular loop of wire 18, which is adapted to encircle the tray 10 transversely, the bottom 19 and sides 20, 20 of said loop fitting snugly the bottom and sides, respectively, of the tray 10, and the top 21 of said loop being sufficiently above the bottom 19 to overlie the short portion 9 of handle member 8, when the device is in its operative position. At the point 22, where the rectangular loop 18 is completed, said point 22 being offset from the center

of top 21, the wire has a short upward bend as shown at 23, and then is carried outward in a direction substantially transverse to the plane of loop 18 for nearly the length of the tray 10, as shown at 24; at the end of the portion 24, the wire is bent into another and larger loop 25, lying parallel to the loop 18. This larger loop 25 has a bottom 26, and sides 27 and 28, adapted to snugly fit the tray 10. The side 27 of loop 25 is of a height sufficient to let the loop embrace the largest socket member 1, so that the top 29 of said loop will overlie said socket member 1 in substantially the plane of the axis of said member. The other side 28 of said loop is relatively low, and it is connected to the top 29 by a slanting loop portion 30, which adjacent said side 28 may bear advantageously on the surface of handle member 8, to hold the latter in place when said loop 25 is in the operative position shown in Figs. 1 and 2.

In the process of completing the bending of the larger loop 25, the wire constituting said loop is thrust through the space between the bottom of tray 10 and the depressed strip 16 of said bottom, so that the bottom 26 of loop 25 will be confined by said strip 16 against the tray bottom, with the result that the wire device shown in Fig. 4 becomes secured to the tray 10, with the capacity for sliding longitudinally thereon through a distance corresponding to the length of strip 16. So assembled, said device of Fig. 4, in its extreme left hand position, shown in Figs. 1 and 2, acts as a retaining means for all the wrench set parts in the tray 10, since the portion 24, connecting the loops 18 and 25, is so situated as to overlie and substantially contact with all of the socket members 1 to 6 inclusive, while the top 21 of loop 18 and the section 30 of loop 25 hold down the handle 8, as above described. Sliding movement of the retaining device of Fig. 4 to the right, until the bottom 26 of loop 25 reaches the right hand end of strip 16, serves to free all of the wrench set parts for removal, as desired, from tray 10.

In the wrench set here shown, as is often times the case, the smaller socket members are of less depth or thickness than the larger ones, so that while the largest socket 55 1 may fit snugly between the handle 8 and side wall 12 of the tray, with no objectionable endwise play, the smaller sockets, because of their lesser thickness, would be subject to such endwise play. Under these 60 circumstances, the material of the wire retaining device above described may be extended from the point of completion 31 of large loop 25 by a section 32, which is appropriately bent at right angles to provide

an elongated portion 33, running from the 65 large loop 25 back to the small loop 18. This portion 33, as shown in Fig. 1, bears against the inner ends of the smaller socket members, and thus serves to prevent endwise play of said members in the space between the wall 12 and the inner surface of handle member 8.

I claim:

1. A tray or container for the reception on its bottom of the interchangeable socket members and the common handle member of a socket wrench set, in combination with longitudinally slidable means for retaining all of said parts against said bottom, said retaining means comprising wire loops encircling the tray and its contents at opposite ends, and connected to each other by a wire in overlying relation to the intermediate contents of the tray. 75

2. A tray or container for the reception on its bottom of the interchangeable socket members and the common handle member of a socket wrench set, in combination with longitudinally slidable means for retaining all of said parts against said bottom, said retaining means comprising wire loops encircling the tray and its contents at opposite ends, and connected to each other by a wire in overlying relation to the intermediate 80 contents of the tray, and by another wire adapted to confine said socket members against endwise movement. 90

3. A tray or container for the sidewise reception on its bottom of a row of interchangeable socket members of a socket wrench set, and for the flatwise reception 100 on its bottom of the bent-end handle common to all the socket members of said set, said handle extending parallel to said row, with its bent end occupying the space between an end wall of said tray and the end socket member of said row, in combination with a wire retaining device slidable longitudinally of said tray, with portions encircling the same and its contents at opposite ends, said encircling portions being connected by longitudinal portions which hold the socket members against the bottom of said tray and against endwise movement on said bottom. 105

4. A tray or container for the reception 115 therein of the interchangeable socket members and common handle member of a socket wrench set, said parts being held in said tray by a longitudinally slidable wire retaining device having portions which encircle said tray and its contents; one of said encircling portions being confined between the bottom of said tray and an integral deflected portion of said bottom, thereby to prevent complete separation of said device from said tray in exposing the parts of the 120 set for removal from said tray. 125

Dated March 30, 1927.

CLARENCE E. WAKEFIELD.
